Primary Examiner — Deanna L Pratt(74) Attorney, Agent, or Firm — Luedeka Neely Group, PC(57) CLAIM

The ornamental design for a circular picnic table with benches, as shown and described.

DESCRIPTION

FIG. 1 is a top perspective view of the circular picnic table with benches;

FIG. 2 is a bottom perspective view of the circular picnic table with benches;

FIG. 3 is a side elevation view of the circular picnic table with benches;

FIG. 4 is a top plan view of the circular picnic table with benches; and,

FIG. 5 is a bottom plan view of the circular picnic table with benches.

The broken lines illustrate portions of the circular picnic table with benches that form no part of the claimed design.
